COMBINATION PICTURE HOLDER AND PAPERWEIGHT

Doris M. Thompson, Arlington, Va., assignor of one-half to Patrick D. Beavers, Washington,
D. C.

Application June 9, 1950, Serial No. 10,431

Term of patent 3½ years

(Cl. D74—12)

To all whom it may concern:

Be it known that I, Doris M. Thompson, a citizen of the United States, residing at Arlington, in the county of Arlington and State of Virginia, have invented a new, original, and ornamental Design for a Combination Picture Holder and Paperweight, of which the following is a specification, reference being had to the accompanying drawing, forming part thereof.

In the drawing:

The dotted lines in the three views serve to illustrate the disposition of a picture on the holder.

I claim:

The ornamental design for a combination picture holder and paperweight, as shown and described.

DORIS M. THOMPSON.
